COMBINATION FLASHLIGHT, GUN,
AND BILLYVictor B. O'Brien and Eldridge B. Robertson,
Alhambra, Calif.

Application December 27, 1949, Serial No. 135,055

4 Claims. (Cl. 42—1)

1

Our invention relates to a combination flashlight, gun and billy, and included in the objects of our invention are:

First, to provide a combination of this class wherein one or more gun units adapted for the discharge of tear gas, are incorporated in a flashlight case in such a manner as to be fired in the direction of a flashlight beam and which incorporates a novel operating means whereby the gun units may be fired in conjunction with operation of the flashlight or independently thereof.

Second, to provide a device of this class wherein the guns may be effectively locked against accidental operation.

Third, to provide on the whole a compact and efficient weapon to be carried by policemen and guards, as well as the military.

With the above and other objects in view as may appear hereinafter, reference is made to the accompanying drawings, in which:

Figure 1 is an elevational view of our device.

Figure 2 is an end view thereof, taken from the plate 2—2 of Figure 1.

Figure 3 is a longitudinal sectional view thereof, taken through 3—3 of Figure 2.

Figure 4 is a transverse sectional view through 4—4 of Figure 3.

Figure 5 is a partial sectional partial elevational view showing particularly the gun trigger and firing pin mechanism.

Figure 6 is a transverse sectional view through 6—6 of Figure 3.

Figure 7 is a transverse sectional view through 7—7 of Figure 3.

Figure 8 is a fragmentary sectional view through 8—8 of Figure 4, showing the firing pin and gun unit.

Figure 9 is a sectional view through 9—9 of Figure 8, showing the firing pins latched in their retracted position.

Figure 10 is a perspective view of the cocking plate.

Our device includes a tubular battery case 1 adapted to receive batteries 2 and closed at one end by a cap 3 containing a spring loaded contact 4 for engagement with the batteries.

The opposite end of the battery case recess is screw-threaded to receive a tubular body 5. The body 5 includes a boss 6 which extends radially inwardly partly across the battery case 1 and is provided with a collar 7 located eccentrically with respect to the battery case and directed outwardly therefrom. The collar 7 supports the base end of a light bulb 8. The light bulb base is held in place by a spring 10 which engages a ferrule 9 attached to or forming an integral part of a reflector 11 surrounding the light bulb and ex-

2

tending forwardly therefrom. The reflector is held in place by means to be described hereinafter.

The boss 6 supports on its side facing the batteries 2, a spring contact 12 which is insulated from the boss and engaged by the terminal of the adjacent battery. The spring contact 12 extends diametrically across the battery case 1 and is folded upon itself to form a spring end which is engageable with the terminal of the light bulb 8. Normally, the contact 12 is out of engagement but is movable into engagement by a pin 14 of insulating material which is slidably mounted in an axial bore located in the wall of the body 5 and is thus disposed exteriorly of the battery case 1. The pin 14 protrudes from the tubular body and is engageable by a collar 15 rotatably mounted on the battery case 1. For purposes which will be brought out hereinafter, the collar 15 is provided with deep recesses 16 separated by a pair of shallow recesses 17. When the pin 14 enters the deep recesses 16, the flashlight is in its "off" condition and when the pin enters the shallow recesses 17 the flashlight is in its "on" condition.

Attached to the body 5 and extending axially therefrom is a gun body 18. Axially extending screws 19 secure the gun body in place. The gun body is provided with an eccentric opening 20 coaxial with the light bulb 8. The opening is provided with an internal flange behind which fits a transparent covering 21, the margins of which are yieldably engaged by the reflector 11 under urge by the spring 10.

The gun body is provided with one or more (in this case two) gun bores 22. Each gun bore receives a cartridge (not shown) contained in a casing 23. The casing 23 is tubular and of sufficient strength to resist the internal pressures created upon firing the cartridge. The cartridge itself may be conventional and comprise a small explosive charge and tear gas chemicals or other chemicals, or the cartridge may be a small gun unit arranged to fire bullets. In any case, the casing 23 is provided with an external groove 24 near its forward end adapted to be engaged by a latch pin 25 mounted radially in a socket provided in the gun body. One end of the latch pin 25 is exposed so that it may be depressed to release the gun casings 23. A spring 26 mounted within the opening 20 urges the latch pin 25 outwardly to retain the gun casings 23.

The tubular body 5 is provided with a recess in alignment with the gun bores 22. Fitted in this recess is a firing pin block 27 having axial bores in alignment with the gun bores and adapted to receive firing pins 28. A guide plate 29 apertured to admit the extremities of the firing pins 28

separates the firing pin bores from the gun bores. Springs 30 urge the firing pins 28 forwardly. A slot 31 is provided in the firing block between the firing pin bores and apertures communicate between the firing pin bores and the slot 31. 5 Fitted in these apertures are keeper balls 32 which are engaged with the firing pins 28 to hold them in their retracted positions. The keeper balls 32 in turn are held in place by a trigger bar 33 which is reciprocable in the slot 31. The trigger bar 33 is provided with side notches so that the keeper balls may drop therein to release the firing pins upon operation of the trigger bar. A spring 34 yieldably retains the trigger bar 33 in cocked position. The trigger bar 33 extends axially and rearwardly from the body 5 and is recessed as indicated by 35 to clear the collar 15. The collar 15 in turn is notched as indicated by 36, so that when the collar is turned to bring the notch 36 into registry with the recess 35, the 10 trigger bar 33 may be actuated.

Axially slidably on the tubular body 5 is a cocking sleeve 37 which carries a cocking plate 38 having lugs 39 which ride in slots formed in the firing pin block and communicates with the firing pin bores. When the cocking sleeve 37 is moved rearwardly, that is, away from the gun body 18, the firing pins 28 are likewise moved rearwardly against the action of their springs 30 until latched by the keeper balls 32. In this condition the exposed extremity of the trigger bar 33 clears the notch 36 in the collar 15 so that the collar 15 may be rotated. Upon rotation of the collar 15 to place its notch 36 out of registry with the trigger bar 33, the trigger bar is restrained against forward or firing movement. The pin recesses 16 and 17 in the collar 15 are so arranged that the flashlight may be turned off and on with the trigger bar cocked but locked against firing. Still further, the recess 36 has sufficient width that the flashlight may be turned off and on while the trigger bar is in its cocked but unlocked position.

Operation of our combination flashlight, gun and billy is as follows:

When desiring to use the device solely as a flashlight, the collar 15 is turned so as to place the notch 36 out of registry with the trigger bar 33. While out of such registry, the collar 15 may be turned to move one set of depressions 16 and 17 past the pin 14 to open or close the circuit to the bulb 8.

When desiring to permit operation of the gun, the collar 15 is rotated until the notch 36 is in registry with the trigger bar 33. This brings the other set of depressions 16 and 17 into position for operation of the pin 14 to open and close the circuit to the bulb 8.

Under the condition of registry between the notch 36 and trigger bar 33, the trigger bar may be moved forwardly by the user's thumb. In doing so, the key bolts 32 release the firing pins 28, causing the cartridge contained in shell 23 to fire.

The head formed by the members 18 and 37 65 forms an effective club or billy when wielded by the handle or battery case 1.

Having fully described our invention, it is to be understood that we do not wish to be limited to the details herein set forth, but our invention 70 is of the full scope of the appended claims.

We claim:

1. A combination of the class described, involving: a body structure defining a flashlight cavity and a gun bore at one side thereof; a 75

flashlight unit in said flashlight cavity; a gun unit adapted to fit said gun bore; firing means for said gun unit including a trigger bar; switch means for said flashlight unit including a rotatable collar; said rotatable collar and trigger bar being engageable with each other whereby for certain positions of said collar said trigger bar may be actuated and for certain other positions of said collar said trigger bar is locked against operation.

2. A combination of the class described, involving: a body structure defining a gun bore adapted to receive a gun cartridge, and a flashlight cavity offset from said gun bore; a battery case connected to said body structure and forming a handle therefor; a flashlight unit in said flashlight cavity, a control means therefor including a collar journaled about the axis of said body, a contact member and a connecting member between said contact member and collar; firing means for a cartridge recessed in said gun bore, said firing means including a firing pin and a trigger bar, said trigger bar protruding from said body structure and traversing said collar; said collar being movable between a position restraining said trigger bar and a position permitting operation thereof.

3. A combination of the class described, involving: a body structure defining a gun bore adapted to receive a gun cartridge, and a flashlight cavity offset from said gun bore; a battery case connected to said body structure and forming a handle therefor; a flashlight unit in said flashlight cavity, a control means therefor including a collar journaled about the axis of said body, a contact member and a connecting member between said contact member and collar; firing means for a cartridge recessed in said gun bore, said firing means including a firing pin and a trigger bar, said trigger bar protruding from said body structure and traversing said collar; said collar being movable between a position restraining said trigger bar and a position permitting operation thereof; and a sleeve axially slidably on said body structure to cock said firing pin for subsequent release by said trigger bar.

4. A combination of the class described, involving: a body structure defining a gun bore in its peripheral portion extending parallel to the axis of said body structure and adapted to receive a gun cartridge; a firing pin for engaging said gun cartridge; a trigger bar also extending parallel to the axis of said body structure, means operable to cause said trigger bar to restrain said firing pin; a sleeve carried by said body structure operable to cock said firing pin for subsequent release by said trigger bar; means rotatable with respect to said body structure for locking said trigger bar to restrain said firing pin in its cocked position; a flashlight unit disposed in said body structure; a battery case extending from said body structure; and a switch for said flashlight unit operable by said rotatable means.
